UNITED STATES PATENT OFFICE

164,471

ARTIFICIAL DENTURE

Morris Beresin, Philadelphia, Pa.

Application June 25, 1948, Serial No. 147,204

Term of patent 14 years

(Cl. D24—1)

To all whom it may concern:

Be it known that I, Morris Beresin, a citizen of the United States, residing at Philadelphia, in the county of Philadelphia, State of Pennsylvania, have invented a new, original, and ornamental Design for an Artificial Denture, of which the following is a specification, reference being had to the accompanying drawing, forming part thereof.

Figure 1 is a front elevational view of an artificial denture, showing my new design;

Figure 2 is an elevational view of one side of said denture;

Figure 3 is a plan view of the underside of the said denture.

The characteristic and dominating features of the design of the invention reside in the portions shown in solid lines.

I claim:

The ornamental design for an artificial denture, substantially as shown and described.

MORRIS BERESIN.
